UNITED STATES PATENT OFFICE.

GEORGE A. LIPPINCOTT, OF PHILADELPHIA, PENNSYLVANIA.

MACHINE FOR SPLITTING PEARL-BUTTON BLANKS.

Application filed April 16, 1926. Serial No. 102,544.

The present invention relates to improvements in machines for splitting pearl button blanks, and has for its object to provide a simple, relatively inexpensive, but very efficient, means, by which pearl button blanks may be rapidly split or separated into discs of the desired thickness.

In the manufacture of pearl button blanks it has been customary to employ rotating 10 saws for separating the blanks, and also in cases where the grain of the material is suitable manually operated chisel and hammer devices have been employed.

The method of forming the button discs 15 by sawing necessarily involves a considerable waste of material, and the hand splitting method heretofore used is necessarily somewhat slow, and also requires a considerable amount of skill on the part of the 20 operator. By such method also it is very difficult to produce discs of uniform thickness.

By the present invention an automatic machine means, acting upon the several blanks 25 in substantially the same manner as the manual chisel and hammer devices heretofore employed, whereby there is no waste of material, is provided. The invention resides in the construction and arrangement of parts 30 that will be hereinafter more particularly described in connection with the accompanying drawings.

In the drawings:—

Figure 1 is a plan view of a machine embodying the present invention.

Figure 2 is a plan, of a portion of the machine on a larger scale, showing the splitting means in a different position.

Figure 3 is an edge view of parts shown 40 in Figure 2.

Figure 4 is a section substantially on the line 4—4 of Figure 2.

Figure 5 is a section substantially on the line 5—5 of Figure 2.

Referring to the drawings, in the several figures of which like reference characters designate corresponding parts, 1 designates a rotary blank holder which is mounted on a vertical shaft 2 journalled in suitable bearings in a supporting frame and connected by gearing, not shown, with a power shaft 3.

Any suitable means may be provided for controlling the rotation of the holder 1.

As shown, the holder is mounted to rotate above a table 4 having a greater area

than the holder, and is provided with a radially projecting annular flange 5 at its upper face, through which a series of vertical passages 6 are formed, in which the blanks to be cut are positioned. The peripheral face of the reduced section of the holder is shown as provided with a series of shallow vertical grooves 6^a in alignment with the passages 6 in the flange 5.

On the table 4 beyond the periphery of the 65 rotary blank holder are mounted the chisel-like splitting devices. In the embodiment of the invention illustrated there are two sets of splitting means, arranged at diametrically opposite points, but it will be appreciated that the invention is not in any manner limited to the number of such devices and that they can be increased, or, if desired, only a single splitting means may be employed with each rotary holder. 70

As shown, each splitting device includes a lever 7, which is fulcrumed at one end, as at 8, on a stud rising from the table 4, and has at its free end a pivotally mounted knife or chisel 9, of circular form. A pin 80 10 rising from the table extends through an opening in the chisel supporting arm 7 and limits movement of the chisel toward the axis of the rotary holder while permitting the chisel 9 to contact successively with the 85 blanks positioned in the passages 6, 6^a as the holder rotates.

A spring 11 is shown as cooperating with the chisel supporting arm 7, to normally hold it in such position that the chisel or 90 knife 9 carried thereby will contact and bear lightly upon the several blanks as they are successively carried past by rotation of the holder 1.

Means are provided whereby the chisel 95 supporting arm 7 is intermittently struck a sharp blow which will, through the sharpened edge of the chisel 9, effectively split the blank with which the chisel is then in contact.

Various means for delivering such sharp quick blow to the chisel may be provided. As shown, the rotary holder 1 is provided on its upper face with a series of upwardly projecting pins or studs 12 and these successively contact with the bevelled edge 13 of a hammer member 14, which is mounted to reciprocate in a suitable guide 15 provided on the table. The body of the hammer 14 is reduced to provide an outwardly 100 105 110

extending shank or stem which extends through an abutment or bracket at 16 on the table 4.

A coiled spring 17 surrounds the reduced stem or shank of the hammer between the shoulder formed between said stem and the body of the hammer and the abutment 16, said spring acting to force the hammer radially toward the axis of the rotary holder 1 when the inner end of the hammer passes from engagement with the pins 12. A pin 20 depending from the hammer member 14 contacts with the chisel supporting arm 7 when the hammer is impelled toward the axis of the holder by the action of the spring 17, and, as before described, imparts a sharp sudden blow to the chisel which effectively splits the blank. Movement of the hammer 14 is guided by a suitable guide 21 secured to the table 4 and the force of the blow imparted by the spring 17 is controlled by adjustment of the abutment 16 radially of the holder. The member of the abutment 16 which extends beneath the table 4 is provided with a slot through which extends the screw 22 that secures it to the table and this connection permits of the necessary radial adjustment of the abutment bracket to vary the power of the spring 17 as desired. A nut 30 screwed upon the outer end of the stem or shank of the hammer cooperates with the abutment 16 to limit inward movement of the hammer.

In the embodiment of the machine illustrated the table or supporting frame 4 is provided with two sections 40 upon which a mass of the blanks to be separated may be supported. An operator adjacent each of said table sections 40 will place the blanks to be split in the passages 6 and as the table rotates they will be successively carried past the adjacent splitting device.

As each pin 12 passes the cooperating hammer 14 the latter will be given a slight movement radially of the holder and under the influence of its cooperating spring 17 caused to impart a sudden sharp blow to the chisel supporting arm 7, and through the chisel carried thereby to the blank which is then in contact therewith. This will sever the blanks and the separated parts will fall through the passages 6 and as the holder turns these parts will fall through a suitable slot 50 formed in the table 4.

While many of the purposes of the invention may be effected if a straight blade-like knife or cutter is employed, it is preferred to make the cutter, as shown, of circular form. A knife or chisel of this particular form has a maximum extent of cutting edge, and requires less frequent sharpening than would be required if it were in the form of a straight blade.

As shown, each splitting means includes but a single cutting blade. However, if de-

sired, the arm 7 may be provided with two or more superposed chisels, whereby three or more discs can be split from each blank at every operation of the hammer devices.

It is believed that the operation and advantages of the invention will be readily understood from the foregoing description in connection with the drawings.

The machine provides a very efficient and rapid means for accurately splitting "straight grain" button blanks into discs of uniform thickness without any waste of material as necessarily results if a saw is employed for severing the blanks.

In the drawings some of the parts are shown more or less conventionally and diagrammatically and, of course, the invention is not limited to the exact proportions shown. Also there may be modification in the shape or form of the parts from that illustrated without departing from the invention.

The drawings are to be considered as illustrative rather than restrictive of the invention, except where the appended claims are specific to the exact details shown.

Having thus described the invention, what is claimed is:—

1. In a machine for splitting button blanks, the combination of a holder adapted to support a plurality of blanks, a cutting blade bodily movable in a plane intersecting one of the blanks in the holder, means for effecting relative movement between the holder and blade to position the blanks successively in the path of the blade, and a spring adapted to have power stored therein by movement of the holder for causing the blade to impart a sudden blow to the blank positioned in its path.

2. In a machine for splitting button blanks, the combination of a rotary holder adapted to support a plurality of blanks, a cutting blade mounted on a relatively stationary support and bodily movable in a plane intersecting one of the blanks in the holder, the blanks being successively positioned in contact with said blade as the holder rotates, and means including a spring adapted to have power stored therein by movement of the holder for causing the blade to impart a blow to the blank positioned in its path.

3. In a machine for splitting button blanks, the combination of a rotary holder adapted to support a plurality of blanks, a cutter comprising a blade and a pivotally mounted arm supporting such blade, and adapted to turn about an axis substantially parallel to that of the blank holder, means for moving the holder to cause the blade to contact with the blanks in the holder successively, and means for intermittently imparting a sharp blow to the cutting blade to split the blank in contact therewith.

4. In a machine for splitting button blanks, the combination of a movable holder

adapted to support a plurality of blanks, a cutter blade carried by a support adapted to turn about an axis extending substantially at right angles to the path of movement of the 5 holder, means for moving the blank holder relative to the cutter blade support to position the blanks successively in contact with the cutting blade, and intermittently acting means controlled by movement of the holder for imparting a sharp blow to the cutter 10 support to move it bodily about its axis and cause the blade to sever the blank in contact therewith.

5. In a machine for splitting button blanks, the combination of a table-like support, a rotary holder mounted above said table and provided about its periphery with means for receiving a series of blanks, a cutter blade arm pivotally mounted on the support beyond the periphery of the blank holder to swing to and from the path of the blanks in the holder as the latter rotates, means acting to hold the blade of said arm against the blanks successively as the holder 20 rotates, and means for intermittently imparting a sharp blow to the blade arm to cause the blade to sever the blank in contact therewith.

6. In a machine for splitting button blanks, the combination of a bodily movable cutter, a holder adapted to support a plurality of blanks, means for moving the holder to carry the blanks across the path of the cutter and successively position them 35 in contact with the cutter, a spring impelled hammer adapted to impart a blow to the cutter while the latter is in contact with a blank, and means controlled by movement of the holder for intermittently effecting 40 actuation of the hammer.

7. In a machine for splitting button blanks, the combination of a rotatable holder adapted to support a plurality of blanks, a cutter adapted to move bodily in a path intersecting the path of movement of blanks 45 by the holder, means for turning the holder

to carry the blanks across the path of the cutter and position them successively in contact with the cutter, a hammer adapted to reciprocate in a path extending radially of 50 the holder, a spring acting to move the hammer into engagement with the cutter, and means controlled by movement of the holder for moving the hammer in opposition to the spring and releasing it to actuate the hammer 55 to effect a blow upon the cutter while the latter is in contact with a blank.

8. In a machine for splitting button blanks, the combination of a bodily movable cutter, a holder adapted to support a plurality of blanks, means for moving the holder to carry the blanks across the path of the cutter and successively position them 60 in contact with the cutter, a hammer, a spring acting to move the hammer into engagement with the cutter, and means on the blank holder adapted to intermittently move the hammer in opposition to the spring and to permit the spring to actuate the hammer 65 to effect a blow upon the cutter while the latter is in contact with a blank.

9. In a machine for splitting button blanks, the combination of a bodily movable cutter, a holder adapted to support a plurality of blanks, means for moving the 75 holder to carry the blanks across the path of the cutter and successively position them in contact with the cutter, a hammer having a member projecting over the holder and a member adapted to engage the cutter, a 80 spring acting to move the hammer into engagement with the cutter, and means on the blank holder for intermittently cooperating with the adjacent member of the hammer to move the hammer in opposition to the spring 85 and to permit the spring to move the hammer to effect a blow upon the cutter while the latter is in contact with a blank.

In testimony whereof I have hereunto set my hand.

GEORGE A. LIPPINCOTT.
